Application November 19, 1934, Serial No. 753,704

4 Claims. (Cl. 126—99)

This invention relates generally to furnaces and refers more particularly to the combustion chambers of warm air furnaces.

One of the essential objects of the invention is to form a combustion chamber in such a way from lighter gauge metal that the heating area thereof in direct contact with the fire can be doubled without adding weight thereto.

Another object is to provide a combustion chamber wherein the formation referred to adds materially to the strength and rigidity of the structure and effectively prevents it from warping or twisting out of shape while in use.

Another object is to provide a combustion chamber embodying the foregoing and comprising several sections which are separately formed but rigidly united in superposed relation.

Another object is to provide a combustion chamber wherein the sections just mentioned differ in diameter but have the same surface area per unit of height.

Another object is to provide a combustion chamber wherein the formation previously mentioned cooperates with the fire brick lining of the fire box portion of the chamber to form ducts for the passage of air upwardly from suitable openings in communication with the ash pit of the furnace.

Another object is to provide a combustion chamber wherein the openings just mentioned are formed in a ring which is rigid with the ash pit walls and forms a common support for the combustion chamber and fire brick lining.

Other objects, advantages and novel details of construction of this invention will be made more apparent as this description proceeds, especially when considered in connection with the accompanying drawings, wherein:

Figure 1 is a vertical sectional view through a furnace embodying our invention;

Figure 2 is an enlarged fragmentary perspective view thereof with parts broken away and in section;

Figure 3 is a horizontal sectional view taken on the line 3—3 of Figure 1;

Figure 4 is a horizontal sectional view taken on the line 4—4 of Figure 1;

Figure 5 is a horizontal sectional view taken on the line 5—5 of Figure 1;

Figure 6 is an enlarged fragmentary top plan view of the dome section of the combustion chamber with parts broken away;

Figure 7 is a sectional view taken on the line 7—7 of Figure 6;

Figure 8 is a sectional view taken on the line 8—8 of Figure 5.

Referring now to the drawings, A is the ash pit, B is the combustion chamber, C is the radiator, and D is the outer casing of a warm air furnace embodying our invention. As shown, the ash pit A has suitable upright walls 1 and a horizontally disposed frame 2 provided with a suitable closure 3. The combustion chamber B is preferably formed of relatively light gauge sheet 10 steel and preferably comprises three sections 4, 5 and 6, respectively. The lower section 4 comprises the fire box portion of the combustion chamber and preferably rests upon a ring 7 welded to the upright walls 1 of the ash pit at the top thereof. The intermediate section 5 is substantially frusto-conical in configuration and is welded in overlapping relation to the lower section 4 at the top thereof. The upper section 6 comprises the dome portion of the combustion chamber and is welded in overlapping relation to the intermediate section 5 at the top thereof. The radiator C preferably encircles the dome section 6 of the combustion chamber and is supported thereon by suitable brackets 8. Preferably this radiator C is connected to the dome section 6 by a flue 9 and is provided at diametrically opposite points with a clean-out passage 10 having a suitable closure 11 and a smoke outlet or flue passage 12. Casing D is conventional in form and encloses the ash pit A, combustion chamber B, and radiator C. As usual, the casing D has suitable openings for receiving the ash pit frame 2, fire box passage 13, and clean-out and flue passages 10 and 12, respectively, and is provided at the top with warm air ducts 14. The grates 15 at the bottom of the combustion chamber and the shaker mechanism 16 preferably correspond to the structure set forth in our application filed October 22, 1934, bearing Serial No. 749,440 and form no part of the present invention.

In the present instance the lower and intermediate sections 4 and 5 and the upright walls of the dome section 6 of the combustion chamber are formed from flat substantially rectangular-shaped light gauge sheet metal plates of uniform length. Preferably such plates are crimped by a die (not shown) so that they will have the corrugated formation shown. One of said corrugated plates is bent to form the circular lower section 4 and opposite ends thereof are arranged in overlapping relation and welded together to complete the formation of said section. Another of said plates is bent to form the frusto-conical intermediate section 5, it being understood, of

course, that the corrugations at the top of said section are pressed closer together to obtain the contracted upper end thereof and the frusto-conical form. The overlapping ends of said second sheet are welded together to complete the formation. The remaining corrugated plate is bent to circular form and its corrugations are uniformly pressed closer together from top to bottom to form the upright walls of the dome section 6. 5 The concavo-convex top 15' of the dome section is formed separately and is placed upon and welded to inturned portions 16' of the upright walls of said dome section as illustrated in Figures 6 and 7 of the accompanying drawings. 10 Thus, it is apparent that the corrugated formation of the plates permits them to be bent into various shapes. In fact, the finished sections 4, 5 and 6 need not be circular as shown. They could be square or some other suitable configuration if desired. 15

After being separately formed, the sections 4, 5 and 6 are welded together in superposed relation as illustrated in Figures 1 and 2 of the drawings. Preferably the lower section 4 rests on the ring 7 between a flange 17 thereof and the upright walls 1 of the ash pit, while a suitable fire brick lining 18 rests upon the ring 7 and flange 17 and cooperates with the grooves formed by the corrugations to form ducts 19 20 for air. Suitable openings 20 are formed in the ring 7 at spaced points thereof in vertical alignment with certain of the ducts 19 to enable air from the ash pit A to pass upwardly between the fire brick lining 18 and combustion chamber section 4 to the interior of the combustion chamber below the frusto-conical section 5 to aid combustion of fuel in the fire box portion of the chamber. Thus, the air is preheated by the fire brick lining 18 before it enters the fire box portion of the combustion chamber. 25

From the foregoing it will be apparent that we have provided a simple but very efficient furnace construction. The corrugated structure provides practically double the heating area in direct contact with the fire and obviates the use of fins and similar means heretofore employed for obtaining increased heating or radiating surfaces. Lighter gauge metal is used and the manufacture and assembly of separate fins have been dispensed with entirely, hence the combustion chamber is less expensive to make than heretofore. Regardless of the diameter of the sections 4, 5 and 6, the heating area per unit of height of all of said sections is constant. Thus, the heating area per unit of height in a given horizontal plane at the top of the combustion chamber is the same as at the bottom. In fact, it has been found that the radiator C may be smaller due to 30 35 40 45 50 55

the greater heating surface of the combustion chamber.

In use the combustion chamber may be installed in either a coal or gas furnace. It could be used as a heating element in a hot water heater. In all uses, the corrugated structure adds to the rigidity permitting strength with lighter gauge metal. It permits the passage of air upwardly beside the fire brick lining 18 so as to be preheated before entering the fire box portion of the combustion chamber. It permits the formation of the frusto-conical section such as 5 of the combustion chamber by merely pressing toward each other the corrugations at one end of the circular formation, and permits the connection 15 of a relatively small circular section such as 6 to a larger circular section such as 4. In other words, the corrugated construction permits the external area per unit of height of all of said sections 4, 5 and 6 to be constant. Regardless 20 of whether the combustion chamber is installed in either a coal or gas furnace, the larger end of the frusto-conical intermediate section 5 is in communication with a source of heated gases in the fire box portion 4 of said chamber, while 25 the smaller end of the intermediate section is in communication with the flue outlet 12.

What we claim as our invention is:

1. A furnace combustion chamber having two cylindrical portions of different diameter formed 30 from two sheets of the same length, and an intermediate portion joining the two cylindrical portions, the external area per unit of height of all of said portions being constant.

2. A furnace combustion chamber having a 35 tapered portion, the larger end thereof being in communication with a source of heated gases, and the smaller end thereof being in communication with a flue outlet, the external area per unit of height of said portion being constant. 40

3. A furnace combustion chamber having upper and lower substantially cylindrical portions of different diameter, and an intermediate frusto conical portion tapering upwardly from the lower portion to said upper portion, each of said portions having substantially vertically extending corrugations, the corrugations of the upper portion being narrower than the corrugations of the lower portion, and the corrugations of the intermediate frusto conical portion varying in width 50 from the lower to the upper portions and merging with the respective corrugations thereof. 45

4. A furnace combustion chamber having two substantially cylindrical portions of different diameter formed from two sheets of the same 55 length, the external area per unit of height of said portions being constant.
